(57) CLAIM

The ornamental design for an hair dryer with hair iron, as shown and described.

DESCRIPTION

FIG. 1 is a perspective view of the hair dryer with hair iron
FIG. 2 is a perspective view of body of FIG. 1;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a plan view of FIG. 1;

FIG. 8 is a bottom view of FIG. 1;

FIG. 9 is a front view of body of FIG. 1;

FIG. 10 is a rear view of body of FIG. 1;

FIG. 11 is a left side view of body of FIG. 1;

FIG. 12 is a right side view of body of FIG. 1;

FIG. 13 is a plan view of body of FIG. 1; and,

FIG. 14 is a reference diagram showing name of each element of FIG. 1.

The broken lines in the drawings are for the purpose of illustrating portions of the hair dryer with hair iron that form no part of the claimed design.
